US00D835587S

(12) **United States Design Patent** (10) Patent No.: **US D835,587 S**
(45) Date of Patent: **** Dec. 11, 2018**

(54) **RECEPTACLE FOR MODULAR WIRING SYSTEMS**

(71) Applicants: **Norman R. Byrne**, Ada, MI (US);
Randell E. Pate, Jenison, MI (US);
Roger D. Burdi, Grand Rapids, MI (US); **Patrick E. Young**, Rockford, MI (US)

(72) Inventors: **Norman R. Byrne**, Ada, MI (US);
Randell E. Pate, Jenison, MI (US);
Roger D. Burdi, Grand Rapids, MI (US); **Patrick E. Young**, Rockford, MI (US)

(**) Term: **15 Years**

(21) Appl. No.: **29/609,852**

(22) Filed: **Jul. 6, 2017**

Related U.S. Application Data

(63) Continuation of application No. 29/553,670, filed on Feb. 3, 2016, now Pat. No. Des. 793,343, which is a continuation-in-part of application No. 14/291,791, filed on May 30, 2014, now Pat. No. 9,257,823.

(57) **CLAIM**

The ornamental design for a receptacle for modular wiring systems, as shown and described.

DESCRIPTION

FIG. 1 is a front perspective view of a receptacle for modular wiring systems showing our new design;

FIG. 2 is another front perspective view taken from an opposite end thereof;

FIG. 3 is a front elevation thereof;

FIG. 4 is a left side elevation thereof;

FIG. 5 is a right side elevation thereof;

FIG. 6 is a bottom plan view thereof; and,

FIG. 7 is a top plan view thereof.

In the drawings, the broken lines depict unclaimed subject matter only and form no part of the claimed design.

1 Claim, 2 Drawing Sheets
